J. J. LEARY.

APPARATUS FOR GENERATING AND BURNING HYDROCARBON VAPORS.

APPLICATION FILED JULY 3, 1916.

1,216,578.

Patented Feb. 20, 1917.

UNITED STATES PATENT OFFICE.

JAMES IHRIE LEARY, OF CHICAGO, ILLINOIS, ASSIGNEE, BY DIRECT AND MESNE ASSIGNMENTS, OF ONE-THIRD TO E. H. DOUD AND ONE-THIRD TO GEORGE LEWIS HOGAN, BOTH OF CHICAGO, ILLINOIS.

APPARATUS FOR GENERATING AND BURNING HYDROCARBON-VAPORS.

1,216,578.

Specification of Letters Patent.

Patented Feb. 20, 1917.

Application filed July 3, 1916. Serial No. 107,354.

To all whom it may concern:

Be it known that I, JAMES IHRIE LEARY, a citizen of the United States, residing at Chicago, in the county of Cook and State of Illinois, have invented new and useful Improvements in Apparatus for Generating and Burning Hydrocarbon-Vapors, of which the following is a specification.

This invention relates to an apparatus for generating a hydro-carbon vapor from a hydro-carbon liquid, such as coal oil, such generation being accomplished by heating the liquid in an inclosed chamber, and the first object of my invention is to provide a simple means of removing carbon residue from the interior of the generating chamber and to limit the formation of oxids within such generating chamber, and the next object of my invention is to provide a simple and compact device for such purpose.

It has been common in the art heretofore to provide a vaporizer for vaporizing hydro-carbon liquids in which the liquid is passed into a generating chamber or retort when it is vaporized, the vapor then passing to a burner, where the vapor burns. In such devices, the burner is arranged to heat the retort.

Such constructions, when used with certain kinds of hydrocarbons, for example, those having a high boiling point, such as kerosene, soon accumulate a deposit of carbonaceous material in the retort and burner, thus finally interfering with the operation of the apparatus.

It has been found that, if, while the retort and burner, with their contained carbon, are hot, a hydro-oxygen cleaning solution such as water be supplied to the retort, the latter will be decomposed and the oxygen will combine with the carbon to form carbonic oxids, particularly carbonic dioxid, which will pass out of the retort and burner in gaseous form, thus clearing these parts of solid carbon deposits. But it has been found that such use of water leads to an oxidation of the iron of which the retort and burner are constructed. This oxid scales off leaving a fresh surface to be readily attacked further and the particles of scale pass on to clog the burner.

It has been recognized that, for the purpose of efficiently heating the liquid and its vapor in order to convert the same into a suitable condition for burning, the passages

for the liquid and vapor should be relatively small in cross-section. Owing, however, to the deposits of carbon, on the one hand, and the formation of oxids, on the other hand, a plurality of small passages for the liquid and vapor leads to difficulties, rendering the use of such a generating chamber commercially impracticable.

I have found, however, that by providing the generating chamber with a plurality of passages, the walls of which are formed of material which is heat-conductive and at the same time undecomposable when heated and subjected to the action of the hydrocarbon vapors and water, it becomes possible to supply the hydro-oxygen cleaning solution, such as water, to the generating chamber at sufficiently frequent intervals to prevent the obstruction of the passages by carbon and at the same time to avoid the formation of any oxids or salts which will scale off.

After considerable experimentation, I have found that by providing the generating chamber with a plurality of passages whose walls are of aluminum, as, for example, by filling the generating chamber with a number of aluminum wires of such cross-section as will leave passages between the wires, for example, by making them of the usual circular cross-section, the apparatus can be kept in continuous operation without danger of clogging, either from deposits of carbon or from oxids and salts formed during the operation of removing the carbon. With such a construction, the mass of aluminum also serves to hold in place any oxid of iron or other scale which may form on the inner wall of the generating chamber, so that the latter cannot drop off. In an apparatus of this kind, the heat necessary for volatilizing a heavy hydrocarbon becomes great enough to cause a softening of the aluminum, but, owing to the way in which the aluminum is held in place in the generating chamber, such aluminum is so supported that it cannot sag down.

The invention, broadly considered, consists of a vapor generator comprising a plurality of passages whose walls are formed of a material undecomposable by the hydro-carbon liquids and vapors and the vapors of the hydro-oxygen cleaning solution at the temperatures necessary for the production of suitable combustible gas.

The invention will now be described in connection with the drawings, and then more particularly pointed out.

In the drawings—

5 Figure 1, represents an elevation view of the complete apparatus, showing a part in sectional view.

Fig. 2, is a vertical section on line 2—2, Fig. 1.

10 Fig. 3, is a transverse section on line 3—3, Fig. 1.

Fig. 4, is a plan view showing the generating chamber and the connected parts.

15 Fig. 5, is an end view of the base of the support for the generating chamber.

In the drawings, A is an oil reservoir preferably square in cross-section and arranged to contain the hydro-carbon liquid, such, for example, as kerosene. Its back projects upward above its top and is provided with a hole, indicated at H, to receive a suitable supporting device, as, for example, a hook K which may be fastened to a wall. The reservoir A is provided with a suitable outlet, 20 arranged to support a screen J through which the oil must pass in leaving the reservoir. Within the reservoir A is arranged a water-conducting tube I held in place by a bracket G and provided at its upper end with an inlet funnel F. The lower end of the tube is open and is arranged to discharge over the screen J of the outlet cup L. An outlet pipe or nipple M is attached to 25 the cup, as by screw-threading. At the end of this pipe M is a valve N for controlling the supply of liquid to the generator. To this valve is attached a suitable connecting tube, indicated at O, which is intended to 30 conduct the liquid to the generating and burning device. This device, in the present embodiment of the invention, comprises a generating chamber of any suitable form, but advantageously constructed as a tube Q.

45 This tube is filled with a plurality of wires of such cross-section that, although they they fill the interior of the generating chamber, they will form the walls of a plurality of passageways which serve to conduct the fluid. In the present example, the wires are 50 of circular cross-section, so that the interstices between the wires constitute the passages. The wires are made of a material which is not susceptible to rapid chemical 55 change or decomposition when heated with hydrocarbon liquids or hydro-oxygen cleaning solutions such as water at the temperature of vaporization of such liquid. By actual experiment, I have found that aluminum wire or fragments are most desirable 60 for this purpose. Since they are efficient in practice and comparatively inexpensive, the mass of aluminum, with the passageways, constitute an efficient device for sub-dividing the liquid and vapors into portions or

streams and at the same time is a good conductor of heat from the walls of the tube Q to such portions or streams of the liquid and vapors. The material constituting the walls of these passages is undecomposable under

70 the action of the heat and vapors, so that when the cleaning solution is injected to burn out any carbon which may be deposited, no scale which can loosen and obstruct the passages or the burner openings, is produced. Furthermore, while the inner wall of the tube Q may be oxidized during the cleaning operation, the oxid is held in place by the mass of aluminum, so that it cannot scale off and pass to the burner openings to 75 obstruct the same. As a result of this, it is practicable to use the cleaning solution frequently and thereby remove any carbon deposits at such frequent intervals as to preserve the passageways practically unobstructed.

80 The tube Q is connected in any suitable manner with a burner tube S advantageously arranged below the tube Q and provided with suitable burner openings 53. In the example shown, the connection between the tubes Q and S is made by ordinary pipe elbows; a connecting nipple joining the elbows. This connecting device is indicated at R, Fig. 1. The end of the pipe S is closed 85 in any suitable way, as, for example, by a cap 13. The tube Q is protected from the direct heat of the flames at the burner openings 53 by suitable deflectors, as, for example, the castings E arranged to slide or 90 turn freely on the tube Q, these deflectors E having flat surfaces at the bottom adjusted directly above or opposite the burner openings 53. The tubes Q and S and their attached parts are supported in any suitable 95 way above a prime lighter of any suitable construction. In the present example, this prime lighter is formed as a tray, indicated at C, having legs X and Y arranged to rest 100 on a grate or other support within a firebox. The tray is filled with a suitable fireproof absorbent, such as asbestos wool. If desired, the generating and burning device 105 may be supported from this prime lighter, as, for example, by providing the tray W with a socket V into which is secured an upright U advantageously in the form of a nipple connected at its other end to an ordinary pipe fitting T, as indicated at T, which fits over the pipe Q and is engaged 110 at one side by a lock nut 12, and on the other side by a coupling P suitably screw-threaded to the pipe Q.

115 The operation of the device is as follows:

120 The generator being set into the firebox of a furnace or stove and the fuel reservoir being filled with a suitable hydrocarbon liquid, such, for example, as coal oil and 125 hung on to the hook K, the valve N is

opened to allow enough liquid fuel to pass through the apparatus and out the burner orifices 53 to saturate the asbestos W. The valve N is then closed and a light applied to the asbestos to ignite the fuel. The heat thus generated heats the tube Q and the aluminum wires. Any liquid in the passages between the aluminum wires is raised to a temperature of vaporization, and the vapor passes through the burner openings 53 and is ignited. At this stage the valve N is again opened, whereby there is a continuous supply of fuel to the generator. This fuel is vaporized by the heat and vapor passing out through the burner openings where it mixes with the air and burns. Each flame strikes the corresponding plate E which spreads it. By a suitable adjustment of the plates E with relation to the pipe Q, the flames may be deflected, as required. The back pressure due to the vaporization of the fluid controls the flow of liquid fuel from the reservoir A.

After the device has been in operation for some time, residue carbon will accumulate in the passages between the aluminum wires. If the operation was permitted to continue long enough, the deposit of carbon would be so great as to clog these passages. Before this condition has arisen, steps are taken to remove the accumulated carbon. This removal operation is as follows:— While the device is burning and the carbon residue is hot, a suitable hydro-oxygen cleaning solution, usually water only, is supplied to the apparatus through the funnel F, as, for example, by dropping it from a medicine dropper. The cleaning solution will pass down through the tube I, the screen J and through the pipe into the generating chamber. At this place the heat will convert the water into vapor and, owing to the presence of the heated carbon, will decompose the vapor. The carbon combines with the oxygen of the water to form carbon-dioxide which will pass out through the gen-

erating chamber, and through the burner orifices. In this way the carbon is removed from the generating chamber, while, on the other hand, no injurious scale is formed to clog the passages or the burner openings. As a result of the invention, heavy hydrocarbons can be vaporized and burned without the troubles heretofore experienced from the deposit of carbon or the interruption of the operation by the formation of scale when removing the carbon.

Having thus described my invention I claim:—

1. In a hydrocarbon generator, the combination with a generating chamber and means for heating the same, of a mass of aluminum within the generating chamber and arranged to come in contact with liquid and vapor passing through the retort, and means for supplying a vaporizable hydrocarbon to the retort, and means for supplying a hydro-oxygen cleaning solution to said retort. 60

2. A vapor generator comprising a vaporizing device with passages having walls of aluminum, said walls being reinforced by a generator wall of conductive material, whereby when heated the aluminum cannot sag. 70

3. A fuel reservoir provided with an outlet in its lower portion, a downward extending tube within such fuel reservoir, the upper end of such tube terminating above the fuel level of such reservoir and its lower end terminating directly over such fuel outlet, an intervening screen between the lower end of such tube and the outlet of such reservoir, and a generating chamber connected with such reservoir outlet at one end and having orifices in its other portions beyond the point of generation, substantially as and for the purpose described. 80
